UNITED STATES PATENT OFFICE.

ALBERT F. F. GILSON, OF CLOSTER, NEW JERSEY, ASSIGNOR, BY MESNE ASSIGNMENTS,
TO WESTERN ELECTRIC COMPANY, INCORPORATED, A CORPORATION OF NEW YORK.

SWITCHBOARD APPARATUS.

1,184,738.

Specification of Letters Patent. Patented May 30, 1916.

Application filed March 20, 1914. Serial No. 326,133.

To all whom it may concern:

Be it known that I, ALBERT F. F. GILSON, a citizen of the United States, residing at Closter, in the county of Bergen and State 5 of New Jersey, have invented a certain new and useful Improvement in Switchboard Apparatus, of which the following is a full, clear, concise, and exact description.

This invention relates to switchboard apparatus and more particularly to party line 10 indicating keys of the mechanically locking type.

The object of this invention is to improve the structure of a key of this type by the 15 provision of few and simple parts which may be easily produced and assembled, and to improve the operation whereby the efficiency is greatly improved and the life of the wearing parts greatly prolonged.

20 In accordance with one feature of this invention, there is provided a longitudinally movable latch plate, through which the plungers extend, and which is provided with anti-friction locking devices for the 25 plungers.

Other features of the invention relate to a novel mounting means for the switch springs and other details of construction and combination of parts as will be hereinafter more 30 fully pointed out.

In the drawings—Figure 1 is a view in side elevation, with parts broken away, of a switch key embodying the features of this 35 invention; Fig. 2 is a perspective view in assembly of parts embodied in the invention, and Fig. 3 is a detail perspective view of a mounting for the switch springs.

As shown in the drawings, 5 designates a top plate of a switch key having mounted 40 thereon a strip of hard rubber or other suitable insulating material 6. Extending through the top plate 5 are spring-actuating plungers 7, 7 having mounted upon the outer ends thereof buttons 8, 8. Formed upon 45 each of the plungers 7 is a conical projection 10 of uniform contour, having a substantially flat upper surface. Secured to each of said plungers 7 is a spring-actuating cam 11 of insulating material also having a uniform conical contour. Secured at 50 their upper ends to the top plate 5 are posts or end members 12, 12, to the lower end of which is secured a spring mounting plate. This spring mounting plate has a main body 55 13 and laterally projecting side members 14,

14. The end members 12, 12 being slotted at 15 to receive one of these side members 14, the other of which projects under the end of the posts as clearly shown in Fig. 2. The mounting plate may be secured to the 60 end members 12, 12 by means of machine screws (not shown).

Located just beneath the top plate 5, and having sliding engagement with reduced portions 16, 16 of the posts 12, 12, is a latch plate 17 having two parallel side members 18, 18 located one upon each side of the plungers 7, 7. Extending transversely of the latch plate 17 and secured to the side members 18, 18, between the ends thereof, 70 are anti-friction rollers 19, 19. These rollers are in position to be engaged by the side face of the conical projection 10 to move the latch plate longitudinally upon the depression of a plunger. A spring 20 secured at 75 one end to one of the end members 12, has its other end in engagement with a turned-over portion 21 of the latch plate 17 and tends normally to hold said latch plate in a position with the anti-friction rollers 19, 80 19 in engagement with the side face of the projections 10, 10, and to move said latch plate into position for the said rollers to engage the upper faces of said projections when the plunger is in a depressed position. 85

In Fig. 3 is shown an integral spring mounting device 30, comprising parallel spring-supporting members 31, 31, mounting lugs 32, 32 stamped from the supporting members 31, 31 and bent at right angles 90 thereto, and an apertured member 33 bent over and adapted to receive the lower end of a plunger 7. This mounting is formed from a single piece of sheet metal and the contact springs 35, 35, 36, 36 and 37, 37, constituting a unit and controlled by one plunger, are secured to the outer faces of the spring-supporting members 31, 31. The total length of the spring mounting device is such that it fits snugly between the lateral side 100 members 14, 14 of the spring mounting plate to which they are secured by means of machine screws which engage the mounting lugs 32, 32.

The plungers are freely rotatable so that 105 in the operation of them, new surfaces upon the projections 10, 10 and the spring-operating cams 11, 11, are constantly being presented to the anti-friction rollers 19, 19 so that the wear on movable adjacent surfaces 110

is equally distributed. The plungers are normally retained in normal position and returned thereto by means of springs 40, 40.

The use of anti-friction locking devices 5 engaging the co-operating projections of the key plunger and the use of a plunger which is free to turn, thus presenting new operating surfaces, has been found to be of great advantage, inasmuch as it prevents the 10 wearing and chipping of the parts and does away with trouble experienced in other forms of keys of having the metal dust resulting from such wear, accumulating between the springs and eventually short-circuiting them. The latch plate comprised 15 of the two parallel side members through which the key plungers extend and connected by means of the anti-friction latch members, is strong and light and is a form which 20 may be readily and economically produced.

The form of spring mounting which is produced from a sheet metal blank is also found to be of great advantage, inasmuch as such a mounting is easily produced at 25 small cost and makes possible the mounting and adjustment of the springs before the assembly of the structure. The use of the channel mounting plate in which the spring mountings fit snugly provides a rigid sup- 30 porting means which retains the mounting and springs in alinement with the operating plunger. Moreover, the use of the separate mounting block for each set of springs, which also forms one support or guide for 35 the corresponding plunger, provides a key structure in which any one of the units, including springs and plunger, may be readily removed for replacement and repair without disturbing other units.

40 What is claimed is:

1. In a switch key in combination a top plate, a plurality of plungers extending through said top plate, said plungers being

free to rotate, a uniform conical projection formed on said plunger, a reciprocating 45 member having two parallel side members located one upon each side of said plungers, and roller members secured at their ends to said side members in position to engage 50 said conical projection.

2. In a switch key, a top plate, a channeled spring mounting plate, means for connecting said plates, contact springs, a stamped U-shaped mounting for said contact springs, means for securing said U- 55 shaped mounting in said channeled mounting plate and a spring operating plunger reciprocally supported in said top plate and said U-shaped mounting.

3. In a switch key, a top plate, a plunger 60 extending therethrough, switch springs controlled by said plunger, a supporting plate for said switch springs having laterally projecting sides, and a mounting device for 65 said switch springs having parallel spring supporting members, punched out supporting ears formed integrally with said side members and an integral apertured portion adapted to receive the lower end of said plunger, said mounting device being secured to said mounting plate between the 70 projecting sides thereof.

4. A punched mounting device for switch springs comprising parallel spring supporting side members, integrally formed mounting lugs punched from and extending at 75 right angles to said spring supporting members, and an apertured plunger supporting member formed integrally with said device.

In witness whereof, I hereunto subscribe 80 my name this 17th day of March, A. D., 1914.

ALBERT F. F. GILSON.
